UNITED STATES PATENT OFFICE.

DAVID L. NORMAN, OF PHILADELPHIA, PENNSYLVANIA.

AUTOMATIC FASTENER FOR WINDOW-CLOSURES.

1,098,832.

Specification of Letters Patent. Patented June 2, 1914.

Application filed September 20, 1913. Serial No. 790,852.

To all whom it may concern:

Be it known that I, DAVID L. NORMAN, a citizen of the United States, residing at Philadelphia, in the county of Philadelphia and State of Pennsylvania, have invented certain new and useful Improvements in Automatic Fasteners for Window-Closures, of which the following is a specification.

My invention relates to improvements in automatic fasteners for window-closures, the object of the invention being to provide improved means for holding a pivoted sash in open position, and permitting the window to close and lock by gravity when a fire occurs.

A further object is to provide improved locking means for a pivoted sash, and improved operating means therefor, embodying in a portion of said operating means, a fusible link which is destroyed by heat or fire, and when destroyed, said operating means permits the sash to close and lock.

A further object is to provide a pivoted sash with locking means at the top and bottom thereof which automatically operate to lock the sash when the latter moves to closed position, and provide improved means for simultaneously operating and controlling both of said locking means.

With these and other objects in view, the invention consists in certain novel features of construction and combinations and arrangements of parts as will be more fully hereinafter described and pointed out in the claims.

In the accompanying drawings: Figure 1 is a view in vertical section illustrating in full lines the sash in open position, and in dotted lines in closed position. Fig. 2 is a view in vertical longitudinal section of the lock operating means for the top of the sash. Fig. 3 is a view in elevation at right angles to Fig. 2. Figs. 4 and 5 are views similar to Figs. 2 and 3 illustrating the locking means for the lower end of the sash, and Fig. 6 is a perspective view of the lock for the upper end of the sash.

1 represents a window frame and 2 a pivoted sash, the pivot 3 thereof being out of the plane of the sash, so that the latter will swing by gravity to closed position.

While I have illustrated a metal frame and sash having beveled ends to form a tight juncture with the metal frame and operate

as a weather seal, I do not limit myself to any particular construction of sash and frame, as my invention is adapted for use in connection with almost any style of pivoted sash and frame.

In the frame 1, at the top thereof, I provide a pivoted lock 4 secured to a bracket 5 fixed within the hollow frame. The bracket 5 has parallel ears 6 for the reception of a pivot pin 7 pivotally securing the lock thereto, and said lock normally falls by gravity, so that it projects through a slot 8 in frame 1 and lies in the path of movement of the upper end of sash 2, locking this upper end of the sash against inward movement.

The lock 4 is limited in its pivotal movement, so that Fig. 1 shows its extreme position. To the sill 9, of frame 1, a bracket 10 is secured, and is provided with a beveled tongue 11 adapted to receive a hook shaped catch 12 pivotally connected by a bracket 13 to the lower portion of the sash, and lock this lower portion of the sash against outward movement.

The bracket 10 is provided at its inner portion below the tongue 11 with a curved finger 14 for a purpose which will herein-after appear.

On the sash 1, at its upper end, a bracket 15 is secured by screws 17, and this bracket has an outwardly projecting lug 18 to which one bifurcated end of a block 19 is pivotally connected by means of a pin 20. The other bifurcated end of a block 19 is pivotally connected by a pin 21 with the lower end of a plunger 22. This plunger 22 extends through a slot 23 in bracket 15, and has an enlarged head 24 at its upper end adapted when the sash is in closed position to lie below the pivoted lock 4.

A hook 25 is pivotally connected to the first-mentioned bifurcated end of block 19 by means of a pin 26, and this hook 25 is connected to the upper end of a chain 27, the latter having a fusible link 28 between its ends, and at its free end provided with a ring 29 to engage the finger 14 above referred to.

A chain 30 connects the pivoted catch 12 with a hook 31 secured on pin 21. As seen most clearly in Fig. 1, the positioning of the ring 29 over the finger 14 holds the sash in open position. In case of fire, the heat will

destroy the fusible link connection 28, so that the sash may fall by gravity to closed position.

When the sash closes, the upper beveled end thereof will move the lock 4 up into the frame until the sash closes, when said lock will fall to locking position as shown in full lines in Fig. 1. At the same time, when the sash closes, the pivoted hook 12 will ride over the tongue 11 and fall into locked position as indicated in dotted lines in Fig. 1.

The unlocking and opening movement of the sash is accomplished by a pull upon the chain 27. A downward pull on this chain 15 will cause the block 19 to fulcrum on the pivot pin 20. This movement of block 19 will elevate the plunger 24 and force the lock 4 up into frame 1. At the same time, such pivotal movement of the block 19 will 20 exert an upward pull on chain 30 to elevate catch 12, and a continued pull on chain 27 will draw the sash to open position when the ring 29 will be positioned over the finger 14, and the sash securely held in this position 25 until the ring is removed or the fusible link destroyed.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a frame and a gravity closing pivoted sash therein, of a locking device adapted to lie in front of the upper end of the sash, a bracket secured to the sash and having a slot therein, a plunger movable longitudinally and vertically through the opening in the slot, a block pivotally connected adjacent one end to the bracket and at its longer end pivotally connected to the lower end of the plunger, said plunger adapted when moved vertically to lift the locking device out of the path of the

sash, and a flexible operating device connected to the shorter end of the block, substantially as described.

2. The combination with a frame and a gravity closing pivoted sash therein, of a locking device adapted to lie in front of the upper end of the sash, a bracket secured to the sash and having a slot therein, a plunger movable longitudinally and vertically through the opening in the slot, a block pivotally connected adjacent one end to the bracket and at its longer end pivotally connected to the lower end of the plunger, said plunger having an enlarged head at its upper end larger than the slot in the bracket, adapted when moved vertically to lift the locking device out of the path of the sash, and a flexible operating device connected to the shorter end of the block, substantially as described.

3. The combination with a frame and a gravity closing pivoted sash in the frame, of a locking device supported in the upper portion of the frame and normally lying in front of the sash, a bracket secured to the upper portion of the sash, a block pivotally connected near one end to the bracket, a plunger pivotally connected to the longer end of the block and guided in its vertical movement through the bracket, said plunger adapted when moved vertically to lift the locking device out of engagement with the sash, a locking device on the lower portion of the sash adapted to engage a fixed device on the frame, a flexible device connecting the pivotal connection of the block and plunger with the last-mentioned locking device, and a second flexible device connected to the shorter end of the block and adapted to engage a part fixed to the frame to hold the sash in open position, substantially as described.

In testimony whereof I have signed my name to this specification in the presence of two subscribing witnesses.

DAVID L. NORMAN.
